DRESS

Matilda M. Mettler, Fort Wayne, Ind.

Application August 9, 1950, Serial No. 178,475

3 Claims. (Cl. 2—74)

1

This invention relates to improvements in a garment of the type known generally as a house dress.

It has been discovered that house dresses ordinarily deteriorate in certain parts more rapidly than in others and become unsightly and useless, while other unworn parts remain available for further use.

An object of the instant invention is to so fashion a garment made of separable parts so the garment serves initially as a complete house dress and subsequently after certain parts of the dress have deteriorated by use, the other unworn parts of the dress may readily be removed from the deteriorated parts and utilized independently as an apron.

Another object of the invention is to unite and secure together the severable parts for initial use as a house dress in such manner that the parts thereof are easily severed when desired.

And a further object of the invention is to afford a house dress having severable parts readily removable from each other to effect economy by salvaging unworn parts for further use.

Other objects and advantages of the invention appear in the following description.

An illustrative embodiment of the invention is shown in the accompanying drawings, in which:

Fig. 1 is a front elevational view of a house dress in which the invention is incorporated;

Fig. 2 is a rear elevational view of the structure shown in Fig. 1;

Fig. 3 is a front elevational view of a severed portion of the dress to be utilized as an apron; and

Fig. 4 is a fragmentary enlarged detail view showing a preferred form of stitching for securing the severable parts of the dress together.

The illustrative embodiment of the invention consists of a house dress, indicated generally by A, in which is included a waist, indicated generally by B, and a skirt, indicated generally by C.

The waist and the skirt are united by an intervening belt 6 that is initially attached around the garment, portions of the belt being separable from certain of the garment parts.

The waist B has sleeve members 7 separably attached thereto, and to the belt 6, and the front of the dress has waist members 8 and 9 that overlap each other and are detachably secured to the adjacent portions of the waist and to the belt 6. Said waist members extend over the top of the garment and are contiguous with each other to form a yoke 10 on the back of the garment. After severance of the sleeve members 7 and the

members 8 and 9 from the waist, and from the belt, there remains permanently shoulder straps 11 and 12 that are contiguous with the back 13 of the garment. The skirt C has front panels 14 and 15, the one overlapping the other, preferably connected together by buttons 16, and are severable from the margins of the skirt adjacent thereto and from the belt 6.

The severable parts indicated generally by D 10 on Fig. 4, have marginal strips 17 and likewise the permanent parts, indicated generally by E, have similar marginal strips 18, which strips are attached together suitably by zigzag stitches 19, or the marginal separable and permanent 15 parts of the dress may be connected together by any suitable form of stitching as by the chain stitch or lock stitch types of sewing.

In use, the dress as a whole is first worn as a house dress until the sleeve members 7 of the 20 waist, the yoke 10 on the back of the waist, the waist members 8 and 9 and the skirt panels 14 and 15 become worn after which the separable parts of the dress including said sleeve members 7, the waist members 8 and 9 and the skirt 25 panels 14 and 15 are removed from the dress completely by ripping the stitching by which the parts of the dress are originally united, thus leaving intact the belt 6, shoulder straps 11 and 12 and the back 13 to be worn as an apron. This 30 operation quickly and completely is accomplished without resort to additional sewing or alterations of the parts of the dress. Thus, the intact permanent parts of the original dress, upon reversal thereof from the back to the front of the wearer, 35 serves as an apron, indicated generally by F.

Preferably, the sides of the skirt C have pockets 20 which remain intact with the back 13 and serve their purpose during use of the dress as such and on the apron after the severable parts 40 have been removed.

A valuable feature of the invention is the arrangement of the strips 17 and 18 around the respective borders of the separable parts of the garment, which strips are temporarily united by 45 the stitching 19 and subsequently ripped to separate the strips from each other and thus detach the several parts of the garment. This is accomplished simply by cutting the stitching that unites the strips. After the parts of the garment 50 have thus been separated the strip 18 that borders the permanent part E serves as a trimming for the apron.

While in the disclosure the invention is referred to as applicable to a house dress, it is also 55 applicable to dresses of other types that may

readily be fashioned to suit the fancy of the wearer without departure from the spirit or scope of the invention simply by varying the patterns for the separable and permanent parts of the garment.

What I claim is:

1. A garment comprising a dress which is convertible to an apron, said garment comprising a skirt, a waist connected to said skirt, a belt encompassing said dress at the juncture of the skirt and waist, said skirt having front panels attached at opposite sides thereof which are severable from the skirt and from said belt, said waist having detachable members and a yoke contiguous therewith, said yoke being detachable from the waist, shoulder straps forming a part of the waist which portions are contiguous with the back part of the dress, sleeve members adjacent the shoulder straps, and rip seams connecting said shoulder straps and the adjacent sleeve members for ready detachment of the same therefrom.

2. A garment comprising a dress which is convertible to an apron, said garment comprising a skirt, a waist connected to said skirt, said skirt having front panels attached at opposite sides thereof which are severable from said skirt, said waist having detachable members and a yoke contiguous therewith, said yoke being detachable from the waist, shoulder engaging portions forming a part of the waist which are contiguous with

the back part of the dress, and rip seams connecting said detachable parts whereby to render the dress convertible to an apron.

3. A garment comprising a dress which is convertible to an apron, said garment comprising a skirt portion, a waist portion, said skirt having front panels which are severable from the skirt at opposite sides thereof, a yoke contiguous with said waist, said yoke being detachable therefrom, shoulder engaging portions forming part of the waist and extending over the shoulder portions forming a contiguous back part of the dress, said back part of the dress after conversion of the dress to an apron forming the front of the apron, and rip seams connecting said detachable portions whereby said portions of the dress can be readily detached therefrom and the dress reversed to provide an apron.
